UNITED STATES PATENT OFFICE.

ALEX. C. WADE, OF PARIS, ILLINOIS, ASSIGNOR TO HIMSELF AND GEO. THILMAN.

IMPROVEMENT IN CHURNS.

Specification forming part of Letters Patent No. 57,051, dated August 7, 1866.

To all whom it may concern:

Be it known that I, ALEXANDER C. WADE, of Paris, Edgar county, Illinois, have invented certain new and useful Improvements in Churns; and I do hereby declare the following to be a full, clear, and exact description thereof, reference being had to the accompanying drawing, making part of this specification.

The object of this invention is to provide a simple, cheap, and effective churn, which can be operated in the most convenient manner, and the working parts being so arranged as to permit of their removal in a few moments for the purpose of cleaning, &c.

In the accompanying drawing, which is a transverse vertical section of a churn embodying my improvements, A represents the tub, which consists of a rectangular vessel having a concave bottom, B, and supported on feet C C'. D is the lid, provided with a slot, E, and said lid is attached to the tub A by means of the buttons d d'.

The under part of the lid is provided with downwardly-projecting shoulders F F', which bear against the inner vertical sides of the tub A, and said shoulders have attached to them the cleat G, which affords journal-bearings for the rock-shaft H of the double-winged dasher I. The dasher I is composed of two wings, J and K, which are provided with a number of dashboards, j j' and k k'.

L is a removable frame, whose ends are connected together by the deflecting-boards N N' and the longitudinal rails O O' O'', which divide the vessel A in two equal parts, but at the same time permit a constant and thorough circulation of the cream from one end to the other of said vessel. P is the lever by which the rock-shaft H and its double-winged dasher I are operated.

Operation: The lever P being depressed, as

shown in the drawing, causes the rock-shaft H to turn in its bearings, by which act the wing K of the dasher I is advanced toward the rails O O' O'', carrying the cream along with it. The cream passes through the interstices between the rails O O' O'' and the dashboards j j', and after striking against the deflecting-board N it falls back into the concave bottom of the vessel. As the lever is elevated the wing J acts on the cream in precisely the same manner, and this alternate elevation and depression of the lever produces the most thorough and complete agitation and circulation of the cream, by which means butter of the most superior quality is produced in a very few minutes.

This mode of operating the dasher by means of the lever P enables a person to sit down while churning, so that invalids and aged persons can perform as much work as the able-bodied with the old kind of churns.

When a sufficient quantity of butter has been produced the churn can be readily cleansed. To do this it is only necessary to turn the buttons d d', so as to enable the lid D, with its annexed rock-shaft H and dasher I, to be disconnected from the box A, after which the removable frame L is lifted out, and having been scalded, they are as easily replaced in their previous position.

I claim herein as new and of my invention—

The double-winged beater I J K, journaled to the lid D, as described, in combination with the removable frame L and its accessories N N' O O' O'', all arranged and operating as explained and set forth.

In testimony of which invention I hereunto set my hand.

ALEXANDER C. WADE.
